METHOD FOR DETERMINING THE NATURE
OF FORMATIONS ENCOUNTERED IN
WELL DRILLINGDaniel Silverman and Robert W. Stuart, Tulsa,
Okla., assignors to Stanolind Oil and Gas Com-
pany, Tulsa, Okla., a corporation of Delaware

Application July 16, 1940, Serial No. 345,734

1 Claim. (Cl. 73—51)

This invention relates to the art of determining the nature of formations encountered during well drilling and apparatus therefor. More particularly it relates to a method of determining the amounts of substances, such as crude oil, salt water, limestone, gas, etc., contained in formations encountered during the drilling of a well by the rotary method, and still more specifically to a method of achieving this result by observation of the properties of drilling fluids which contain cuttings of the formations penetrated.

Many methods have been devised for the purpose of obtaining some information as to the nature of the various formations traversed by a well, such as the well-known electrical logging methods whereby such indications are obtained by means of appropriate electrical measurements. However, electrical logging methods have the disadvantage that they can be carried out readily only upon wells which have already been drilled and they are therefore not well adapted to give information as to the nature of formations penetrated by a drill bit during the actual drilling operation.

More recently a method of mud logging has been developed which consists of taking samples of drilling mud at regular intervals as it returns from the hole and testing these samples for minute amounts of crude oil and gas and/or determining their electrical conductivity, which is a measure of salt content. The method generally used for detecting crude oil in such samples is to subject them to irradiation with ultraviolet light and observe whether or not fluorescence is produced thereby.

Mud logging carried out in this way has the advantage over electrical logging in that it yields information as to the nature of the various strata penetrated by the drill, but it also has a number of disadvantages among which are that accurate determination of the amount of crude oil present is not made when that is the substance for which the test is made, and that there is necessarily a delay regardless of the test applied between the time that the particular mud sample was at the bottom of the well and the time of taking the sample due to the fact that the mud requires a considerable period, which is often of the order of one hour or more, to reach the surface. Obviously, any further drilling during this interval is done without the benefit of the test results, so that undesirable penetration of a water-bearing formation underlying an oil-bearing formation may occur, for example.

We have devised an improved method of mud logging whereby a major part of the time delay mentioned above is eliminated together with most of the undesirable consequences thereof, and in addition the possibility of contamination is substantially eliminated. Broadly speaking,

our invention concerns the application of reverse circulation to mud logging and includes a number of modifications which will be hereinafter fully described.

5 It is an object of our invention to provide a novel method of determining the nature of formations encountered during well drilling by means of tests applied to the drilling fluid. Another object is to provide a system for obtaining 10 rapidly and efficiently information as to the nature of formations encountered during a rotary drilling operation. A still further object is to provide a method and apparatus whereby drilling fluid containing some of the formations being 15 penetrated by a rotary drilling operation can be forced through the drill bit into the drill string and subsequently tested for at least one property indicative of the nature of a substance such as oil, salt, limestone, gas, etc., which was present in that formation and whereby the results of such tests are made available in very short times. Other objects, uses and advantages of our invention will be apparent from the following detailed description read in conjunction with the drawings in which:

25 Figure 1 illustrates schematically a vertical section through the earth's crust and one form of apparatus for practicing our invention;

30 Figure 2 is likewise a schematic illustration similar to that of Figure 1 which shows apparatus for carrying out our invention according to another modification thereof;

35 Figure 3 illustrates one form of oil-detecting apparatus which can be used according to our invention shown in vertical-cross section;

Figure 4 is a horizontal cross-section along line 4—4 of Figure 3;

Figure 5 is a horizontal cross-section along line 5—5 of Figure 3;

40 Figure 6 is a partial cross-sectional view of another form of oil-detecting apparatus adapted to be used according to our invention wherein the indication of the amount of crude oil present in the surrounding fluid is recorded on a photosensitive medium;

45 Figure 7 is a vertical cross-section of an apparatus for measuring the conductivity of drilling fluid within a drill string;

Figure 8 is a horizontal cross-section along line 8—8 of Figure 7;

Figure 9 is a horizontal cross-section along line 9—9 of Figure 7; and

50 Figure 10 illustrates diagrammatically the electrical apparatus and circuit used to record the indications obtained by means of the apparatus of Figure 7.

55 In one of its broadest aspects our invention comprises the determination of the nature of formations encountered during a rotary drilling operation by causing the drilling fluid to pass

through the drill bit from the bottom of the well into the drill string and subsequently testing at least a portion of this drilling fluid for at least one property indicative of the nature of a substance present in the formation being penetrated. In other words our invention comprises testing drilling fluid which has been forced into the drill string by reverse circulation to determine the amount of oil, salt, limestone and/or gas which was originally present in the formation being drilled.

Our invention is not only applicable to situations in which a stratum containing one of these substances has already been penetrated but in the case of oil and gas, at least, our invention will enable the driller to ascertain that he is approaching a formation containing one or both of them since small amounts of oil and gas are known to migrate and to exist in the formations immediately overlying strata containing large amounts of them. Thus, in drilling a well which approaches an oil-bearing formation, the oil content of the drilling fluid constantly increases due to the small amounts of oil present in that portion of the overlying formations carried out of the well in the form of cuttings.

As stated above, the periodic testing of drill mud returns is well-known in the art but involves a disadvantageous delay in obtaining the test results. A considerable portion of this time delay can be eliminated according to one modification of our invention by employing reverse circulation in the entire rotary drilling operation and testing the mud returns for oil and/or other indicating substances. Because of the fact that there is a relatively large volume of drill mud contained in a well between the drill string and the casing or the hole itself and a relatively small volume, which is usually of the order of one-fifth, within the drill string, the drilling mud will reach the surface in approximately one-fifth the time when using reverse circulation that it takes when the usual drilling procedure is employed, and consequently the returning mud can be tested and the results made available in that short time. For example, while a sample of mud may require an hour to reach the surface using ordinary circulation, by using reverse circulation, according to our invention the sample is taken and tested in less than fifteen minutes.

In many instances, however, it is not desirable to use reverse circulation during the entire drilling operation and we have therefore devised a modification of our invention which consists briefly in reversing the circulation of the drilling mud for a short time when it is desired to test the nature of the formation being penetrated or to obtain an indication of the nature of a closely underlying stratum and testing the drilling mud which is in the lower portion of the drill string either by lowering a suitable testing instrument or by taking a sample therefrom by means of a conventional bail and making the test at the surface of the earth. Our invention can best be understood in all its details by reference to the drawings.

Figure 1 illustrates, in highly simplified form, apparatus which can be used in carrying out that form of our invention in which reverse circulation of the drilling mud is employed continuously during the drilling operation. A well 10 is shown bottomed at 11 and having a casing 12 with a mud connection 13 below a pressure packer 14 which provides a seal between the casing and drill stem to give sufficient pressure for re-

verse circulation. Also shown within well 10 is a string of drill pipe 15 having a drill bit 16 at its lower end and a swivel 17 at its upper end. During the drilling operation drilling mud is supplied from mud pit 18 by means of line 19, 20 and 21 to the mud connection 13, whence it passes down the annular space outside the drill pipe 15, picks up cuttings at the bottom 11 of the well and ascends through the usual opening in drill bit 16 and drill string 15 to swivel 17. The returning mud is then sent back to the mud pit after the conventional screening (not shown) by means of line 22, valve 23 and outlet 24. Prior to screening or any other operation, however, a portion of the returned mud passes through valve 25, testing unit 26 and valve 27 on its way to mud pit 18. As above stated, the time required for mud to travel between the bottom 11 of well 10 and mud testing unit 26 is relatively short. Testing unit 26 is adapted to determine continuously the presence and amount of crude oil, the electrical conductivity, the hydrogen ion concentration and/or the gas content of the drilling mud. Each of these tests have been used on a grab sample basis but we prefer to carry out all of these tests continuously and simultaneously.

While the particular tests themselves form no part of the present invention a brief description of the principles employed will be advantageous. The detection of crude oil has heretofore been carried out by subjecting samples of returned drilling fluid to irradiation with ultraviolet light and observing whether or not fluorescence is produced. This fluorescence appears to be a property of the rather complex composition of the crude oil. This composition is changed by refining operation so that the fluorescence emitted by refined oils such as lubricating oils when irradiated by ultraviolet light is sufficiently different from the fluorescence emitted by crude oil that there is no possibility of mistaking one for the other. Furthermore, the difference can be accentuated by the use of appropriate optical filters. This test therefore is a reliable one for the detection and measurement of small amounts of crude oil.

The electrical conductivity test can be carried out in a manner well-known to those skilled in the art, and as applied to drilling muds is indicative of the presence of salt in the drilling mud and hence of salt or salt water in the formation being drilled because the presence of salt very materially increases the electrical conductivity of drilling mud. The hydrogen ion concentration or pH determination can also be carried out according to known principles and serves to indicate the presence of alkaline reacting materials, such as limestone. The determination of natural gas is usually carried out by passing a sample of gas removed from the mud under vacuum and mixing with a stream of air over a resistance maintained at a definite temperature by means of an electrical current and measuring any rise in temperature due to combustion of hydrocarbon gas by noting the increase in the value of the resistance.

In Figure 1 we have indicated that testing unit 26 operates on a continuous basis and we prefer that it should also record continuously all of the properties of the mud tested, but this feature is not essential to our invention since any of these tests may be applied periodically. However, the great advantage of continuously recording the test results, particularly when they are recorded on a strip showing the depth at which the mate-

rial in the mud being tested was originally present, is that an extremely useful log of the nature of the various formations traversed by the well being drilled is obtained.

In the second and usually preferred modification of our invention circulation of the drilling fluid is maintained in the usual direction during most of the drilling operation. Figure 2, which illustrates this modification, shows a well 30 bottomed at 31 and having a casing 32 with a mud connection 33. Also shown is a string of drill pipe 34 having drill bit 35 at its lower end. During the rotation of drill pipe 34 mud is supplied from mud pit 36 through line 37, pump 38, valve 39, line 40 and hose 41 to a swivel (not shown) at the upper end of drill pipe 34. Thence the mud passes down drill pipe 34 through drill bit 35 to bottom 31 of well 30 and up through the annular space around drill pipe 34 together with cuttings of the formation being drilled. The returned mud is withdrawn from the well through connection 33 and goes to mud pit 36 through line 42, valve 43 and lines 44 and 45. During all of this process, mud-testing unit 46 and supporting cable 47, which are also shown in Figure 2, are not present.

At desired intervals of depth or time, or when there is reason to suppose that the drill bit is in or approaching a stratum of interest either by reason of previous tests by the method being described or because the rate of drilling indicates that the bit is in a different formation, or because a producing or other formation of interest is expected at a certain depth, the rotation of drill pipe 34 is stopped and the drilling mud around bit 35, which contains material from the formation composing the bottom 31 of well 30, is forced through bit 35 into the lower portion of drill string 34. This is accomplished by closing valves 43 and 39 and opening valves 48 and 49 so that the direction of flow of the drilling mud is reversed. After a very short time sufficient to cause a substantial amount of drilling fluid to enter drill string 34, mud pump 38 is stopped, the upper end of drill string 34 is broken and the mud in the lower end of drill string 34 is tested for one or more of the indicative properties above-mentioned.

One way of carrying out the testing operation is to lower a conventional wire line bail to obtain a sample of the fluid just above drill bit 35, withdraw it to the surface and test the sample by any of the procedures mentioned.

It is greatly preferred, however, to lower an instrument through drill string 34 which is capable of making the desired test, and this is particularly desirable when the test to be made is for the presence of crude oil or of the electrical conductivity. Figure 2 illustrates the position of testing unit 46 lowered on a cable 47 in carrying out this embodiment of our invention.

It will be apparent that this procedure has the advantage of being very rapid and of giving positive evidence of the nature of the formation being drilled or of a formation being approached during the actual drilling operation, at which time this is most useful.

Any type of mud-testing instrument 46 which will give an indication of at least one property of the mud influenced by the nature of a substance present in the formation being drilled can be used. For the detection and measurement of crude oil, for instance, the oil detecting unit which we prefer, is an ultraviolet irradiating unit and photoelectric pickup for indicating any

resultant fluorescence. Two modifications of this are shown in Figures 3 through 6. Referring to Figures 3, 4 and 5, a hollow steel casing 50 capable of withstanding high pressures is closed at its lower end by a heavy foot portion 51 which provides the weight necessary to cause the unit to sink rapidly through the fluids present in the drill string, and at its upper end by a cap 52 having an axial opening 53 for the entrance of supporting and power supply cable 54 which corresponds to cable 47 of Figure 2. Cable 54 is firmly attached to cap 52 by means of packing assembly 55 which also serves to make the unit fluid-tight.

15 Casing 50 has at one side a window opening 56 completely closed by a window 57 made of quartz or other transparent material capable of transmitting ultraviolet as well as visible light, window 57 being held in position by means of molding 58 and screws 59. Within casing 50 a light-proof chamber 60 supported by brackets 61 contains a source of ultraviolet light 62 actuated by electrical current supplied from the top of the well through cable 54 and leads 63. The source of ultraviolet light is preferably a lamp of the conventional mercury vapor type. Chamber 60 has at its lower end an opening 64 for the emission of ultraviolet light across which filters 65 are mounted, these filters being capable of substantially completely removing both visible and infra-red rays.

30 The filtered ultraviolet light is then directed by suitable means through window 57 in order that it may irradiate fluid outside and in contact with this window. In the present design this is accomplished by means of a bent rod 66 made of quartz, a synthetic resin of the methacrylic type, or other material capable of conducting ultraviolet light axially therethrough. 35 Also mounted within casing 50 by means of bracket 67 in a photosensitive cell 68 enclosed in a light-proof chamber 69 having on one side an opening 70 for the admission of light covered by filter 71 adapted to remove the ultraviolet rays 40 therefrom.

45 Photosensitive cell 68 and filter 71 are arranged in such a way as to receive with a maximum of efficiency any fluorescent light produced by crude oil in the fluid outside of window 57 under the influence of the ultraviolet light directed against it by rod 66. It has been found that the maximum fluorescent emission is obtained when the angle between the ultraviolet rays and the vertical axis of window 57 is of the order of 45°, but this angle may vary between about 40° and about 50°. Furthermore, maximum energization of the photosensitive cell is obtained when the included angle between the fluorescent rays reaching it and the ultraviolet rays as about 20° to about 40°, preferably about 30°.

50 Photosensitive cell 68 can be of any suitable type. For instance it can be of the photovoltaic type such as a copper oxide, silver or selenium cell which requires no auxiliary source of potential. In the apparatus shown in Figure 3 however, photosensitive cell 68 is of the photo-conductive type such as for instance a gas-filled tube using a metallic rubidium electrode. The power 55 to operate this cell is provided by means of leads 72, one of which contains a resistance 73. The variations of conductivity of cell 68 are measured by determining the potential difference across resistance 73, amplifying this potential difference 60 by means of preamplifier 74 and conducting the

amplifier output to the surface of the earth by means of shielded leads 75 which extend through cable 54 for recording in the usual manner.

Another modification employing a photosensitive medium such as a photographic film is shown in Figure 6 which has the same type of ultraviolet light source as the unit already described. In this case a camera 80 is supported in the proper position to receive the fluorescent light entering window 57. This light passes through lens 81 and filter 71 and is recorded on film 82 which is driven from the film magazine 83 to the take-up magazine 84 by means of clockwork mechanism 85. For the sake of simplicity the detailed camera arrangement is not shown but will be obvious to one skilled in the art.

It is apparent that using either of these oil detecting units or an obvious modification thereof, the process described in connection with Figure 2 can be readily carried out as to the detection of minute amounts of crude oil and the measurement of relative quantities thereof in the drilling fluid present in the lower end of drill string 34.

One type of unit for the determination of the electrical conductivity of drilling fluid in the lower end of drill string 34 is shown in Figures 7 and 8. This consists in a tubular body portion 90 of steel or other metal having a foot member 91 attached to its lower end but having a number of openings 92 therethrough for the ingress of drilling fluid. A cap member 93 completely closes the upper portion of body 90 and is supported by cable 94 which also contains suitable electrical conductors by means of packing gland 95. A tubular liner 96 of Bakelite or other electrical insulator is inserted within body portion 90, and within liner 96 two rings 97 and 98 of brass or other conducting metal are located, spaced from each other by tubular insulator 99, ring 97 being spaced from foot 91 by tubular insulator 100. Above ring 98 is another insulating spacer tube 101 and between the latter and shoulder 102 of cap 93 is a disc 103 of insulating material, so that the interior of cap 93 is a chamber 104 which is kept free of mud. During the lowering of the conductivity testing unit, the mud in the drill pipe enters through ports 92 and leaves through ports 105 formed in body 90 and insulators 96 and 101.

The electrodes for measuring variations in conductivity are the rings 97 and 98 already described. Between them two additional electrodes 106 and 107 are supported by means of insulating blocks 108 and 109, respectively, and this entire assembly is completely surrounded by a tube 110 of an insulating material which fits into appropriate openings in tube 99. In this way a separate cell is produced in which a standard sample of drilling mud can be placed without danger of contamination by the drilling mud entering the unit through ports 92 and which allows good heat transfer between the sample within and the drilling mud outside of tube 110.

All of the electrode have electrical connections leading to the top of the well. Insulated conductor 111 connects electrodes 97 and 106 and then extends through longitudinal groove 112 in tube 96, opening 113 and packing gland 114 in insulating disc 103, and cable 94 to the surface of the earth. Electrodes 98 and 107 have a sim-

ilar separate connections by means of conductors 115 and 116 extending through grooves 117 and 118, openings 119 and 120 and packing glands 121 and 122, respectively.

8 It has been found that in the determination of electrical conductivity of drilling muds, the effect of temperature is quite appreciable so that erroneous results will be obtained unless some method of compensating for the rather high temperatures prevalent in a well is provided. Consequently, a mud of known electrical conductivity is placed in the cell enclosed by insulator 110 and the variation in conductivity between electrodes 106 and 107 provides a means for correcting the 15 conductivity of the mud filling the entire unit including the space between electrodes 97 and 98.

Any suitable method of applying this correction can be used and we have illustrated one such method in Figure 1 which also shows the source 20 of power and the recording device diagrammatically illustrated. For this purpose a source of alternating current is used which is indicated by a transformer 130, the output from which is applied across resistance 131 and electrodes 97 25 and 98 through leads 111 and 115 and across resistance 132 and electrodes 106 and 107 by means of leads 111 and 116. It will be seen that this system of resistances constitutes a Wheatstone bridge net work in which the source of potential 30 is applied across one diagonal. The potential difference across the other diagonal of this bridge is applied to a conventional bridge rectifying system 133 and the rectified output is then sent to recorder 134. Obviously, by means of this apparatus variations in the relative resistivities between electrodes 97 and 98 and electrodes 106 and 107 can be obtained under any temperature conditions and a valuable record of the decreased 35 resistance, i. e., increased conductivity of the 40 drilling mud between electrodes 97 and 98 due to increased salt content, is obtained.

It will be readily seen from the above that we have provided a novel system of determining the 45 nature of formations encountered during a rotary well drilling operation which provides precise information as to the presence of oil, salt, etc., in the formations being drilled, and does so in the most rapid fashion. Many other modifications will, of course, be apparent to those skilled 50 in the art in the light of the above disclosure, and these are within the contemplation of our invention.

While we have described our invention in terms 55 of certain specific embodiments thereof, we do not desire to be limited thereto but only by the scope of the appended claim.

We claim:

The method of determining the nature of a 60 formation encountered during a well drilling operation, wherein a circulating fluid is employed, which comprises interrupting said drilling operation, forcing by reverse circulation a small amount of drilling fluid through the drill bit into the drill string above said bit, and testing, within 65 said drill stem immediately above said drill bit, at least a portion of said small amount of drilling fluid for at least one property indicative of the nature of a substance present in the formation being penetrated by said drill bit.

70 DANIEL SILVERMAN.
ROBERT W. STUART.
